ABSTRACT: An outboard motor includes a cowl and frame vibrationally isolated from the engine. A capacitor discharge ignition circuit includes a capacitor connected to a battery through a charging circuit and to the distributor and thereby the spark plugs through a silicon controlled rectifier and pulse transformer. The system components are housed within a metal box which is secured and grounded to the cowl frame. The common or ground side of a battery is directly connected to the grounded cowl frame and the positive side is connected directly to the charging circuit and to the starter. A relatively substantial jumper lead interconnects the cowl frame to the engine block. The transformer is suitably mounted within the outboard motor and connected to the ignition system by suitable leads and to the spark plugs through the usual distributor.

In operation, any high voltage transients developed between the cowl frame and the engine block are not impressed across the ignition system.

SOLID-STATE IGNITION SYSTEM FOR OUTBOARD MOTORS

This application is a continuation of application Ser. No. 539,532 filed Apr. 1, 1966, now abandoned.

This invention relates to a solid-state ignition system for internal combustion engines and particularly to the mounting and connection of engine ignition systems into the engine firing circuit for outboard motors and the like.

Ignition systems of a solid-state or transistorized variety have been suggested for internal-combustion engines. Such units minimize certain problems associated with conventional ignition systems. A highly satisfactory ignition system for internal-combustion engines and particularly outboard motors is shown in applicant's copending application entitled Solid-state Ignition System which is being filed on even date herewith and is assigned to the same assignee as the present application. As more fully disclosed therein, a capacitor is periodically charged through a triggered oscillator and discharged through the firing of a silicon controlled rectifier and pulse transformer. As disclosed in that application, the ignition system is constructed as a potted unit within a suitable metal box with the heat sensitive element secured to the base of the box. The ignition housing or box is directly mounted to a cowl frame in the path of the air passed to the carburetor means to provide maximum dissipation of the heating and to isolate the ignition system from the engine vibrations.

In the development of a solid-state ignition system, failure of the solid-state components was encountered without any apparent reason.

As disclosed in the previously identified copending application, the cowl and its frame are vibrationally isolated from the engine. A jumper lead was normally connected therebetween to prevent creation of high voltages therebetween. The ignition unit was grounded directly to the cowl assembly and through the jumper lead to the engine which was connected to the ground terminal of the battery. Applicant discovered that the inductance associated with the ground jumper and distributor high voltage lead and the capacitance from the high voltage wiring, distributor, and coil secondary to both the cowl and engine block considered with the switching characteristic of the arc gap produced by a spark plug would produce damaging voltage transients between the engine block and cowl. Although this transient is of extremely short duration of the order of 10 nanoseconds (10^{-9} sec.), applicant realized the magnitude of the order of several thousand volts was such that applied directly across the ignition system would damage the units and further that the distributed impedances could not be practically reduced to a degree to prevent such damaging voltages.

The present invention is particularly directed to an improved circuit connection positively preventing application of the high voltage transients across the ignition systems. In accordance with the present invention, the common or ground side of the battery is directly connected to the grounded cowl unit. A relatively substantial jumper lead interconnects the cowl unit to the engine block to form the common interconnection between the ignition system and the engine block as this jumper lead must carry starter current when employing an electric start. The coil is suitably mounted within the outboard motor and connected to the ignition system by suitable leads and to the spark plugs through the usual distributor.

In operation, any high voltage transients developed between the cowl unit and the engine block are not impressed across the ignition system. Consequently, failure of components from the voltage transients has been essentially eliminated.

The present invention thus provides a simple and inexpensive means for maintaining the operation of the ignition system in an internal combustion engine.

The drawing furnished herewith illustrates a preferred construction of the present invention in which the above advantages and features are clearly shown as well as others which will be clear from the following description.

In the drawing:

FIG. 1 is a partial sectional view of an outboard motor with a solid-state ignition system mounted and connected in accordance with the present invention; and

FIG. 2 is a diagrammatic illustration of the outboard motor and the connection of the ignition system into the circuit in accordance with the present invention.

Referring to the drawing and particularly to FIG. 1, an outboard motor 1 for driving a watercraft, not shown, is shown generally corresponding to that described in applicant's previously referred to copending application. The illustrated outboard motor 1 includes an internal-combustion engine 2 supported upon the upper end of a drive shaft housing 3. A suitable drive mechanism, not shown, extends from the engine down through the housing to drive a propeller unit, now shown. The engine 2 is enclosed within an outer cowl assembly 4 including a supporting cowl frame assembly 5 which is attached to and vibrationally isolated from the engine 2 and the drive shaft housing 3.

A solid-state ignition unit 6 is mounted directly to the cowl frame assembly 5. A battery 7 provides an initial source of energy and is connected to the ignition unit 6 and an electric starter 8 through a plug connector 9.

The ignition unit 6 is connected through a transformer 10 for firing of the spark plugs 11. The transformer 10 is mounted within the cowl assembly and connected by a lead 12 to a distributor, not shown, in FIG. 1. The distributor sequentially connects the transformer 10 to the several spark plugs 11 for proper sequential firing of the spark plugs and operation of the engine.

The battery connection includes the plug type connector 9 for releasably interconnecting of the engine circuit to the battery 7 and a remote electrical control 13. The connector 9 includes an external harness 14 connected to the battery 7 and the control 13 and an engine harness 15 secured to the lower cowl member 16. The several leads from the engine harness 15 are described in sufficient detail to clearly describe the invention. One lead 17 which is connected through the connector 9 to the positive or high voltage terminal of the battery 7 is connected directly to the ignition unit 6 while a second lead 18 which is similarly connected to the ground or common battery terminal is connected directly to a cowl frame member 19 to provide the ground connection. A third lead 20 is connected through the connector 9 to the positive or high voltage battery terminal to the starter 8 through a starter solenoid 21. A ground jumper lead 22 interconnects the cowl frame member 5 to the engine block 2 and establishes the ground connection from the starter to the cowl frame.

Referring particularly to FIG. 2, an ignition system is schematically and briefly shown including a capacitor 23 connected to the battery 7 through a DC to DC converter 24 which includes a capacitor charging circuit, now shown. The capacitor 23 is connected in a discharge circuit including the transformer 10 and a silicon controlled rectifier 25. A set of points 26 such as conventional points are shown and are connected in the circuit in any suitable manner to periodically fire the silicon controlled rectifier 25 for discharging of the capacitor 23 into the coil unit 10 and through a distributor 26 into a spark plug 11. For a more detailed description of the ignition system reference may be made to applicant's previously identified application.

In FIG. 2, the cowling and the engine block are diagrammatically shown. Additionally, the jumper lead 22 is shown with a series connected inductance element 27 which indicates the inherent inductance of the lead as such and not a separate element connected in the circuit. The inductance of the coil and distributor leads, the distributed capacitance of the transformer 10 and between the distributor lead and the 70 cowling and between the distributor lead and the engine block is also schematically shown in a similar manner by appropriate lumped elements 28, 29 and 30.

From FIG. 2, a series circuit is formed including the inductance elements 27 and 28, capacitor 29 and the spark plug 75 gap 11. This constitutes an inductance-capacitive circuit

which, when the gap fires, can cause high transient voltages to exist between the cowling and the engine block for short periods, in the order of nanoseconds, but of sufficient magnitude to damage solid-state components.

Prior to firing of the gap, capacitor 29 is charged. When the gap 11 fires, the series circuit is completed and the voltage across the capacitor 29 is divided between inductances 27 and 28. Generally, the inductances are of a similar size and the voltage divides more or less equally. The voltage of capacitor 29 will be of the order required to break down the gap 11 and may easily be of the order of 10,000 volts, with a resulting 5,000 volts appearing across the inductance 27 and therefore between the cowl 5 and the engine 2. Such voltages appearing for the order of nanoseconds are not generally of any serious consequence. However, applicant has realized and discovered that the voltages did damage and in fact often destroyed solid state electronic components.

In accordance with the teaching of this application, the ignition unit is connected directly between the positive and the negative leads of the battery 7 through the common or ground connection to the cowl frame, rather than the usual connection of the battery negative directly to the engine block. This eliminates the superposition of high voltage transients on the battery voltage as applied to the input of the ignition unit 6. Thus, a reliable and improved circuit operation is provided. Thus, applicant has perceived a severe limitation in the normal connection of the battery ground lead directly to the engine and avoided the attendant problem in an exceptionally simple and inexpensive manner.

I claim:

1. In an outboard motor having an internal combustion engine unit with the engine connected to and electrically insulated from a support including a cowl-supporting frame supported upon electrically insulating members providing sub-

stantial electrical impedance at high frequency therebetween, the improvement in the electrical system for the engine comprising an electrical ignition operating unit including an ignition system having solid-state components, means mounting 5 said ignition system on said frame and being grounded to the frame, a battery for said engine including a first lead connected to the ignition system and a second lead directly connected to the frame, a direct current starter for said engine mounted upon the engine and including a first terminal connected through a normally open switch means to the ungrounded terminal of said battery and grounded to the engine, and a ground lead connected between the engine and the frame whereby high voltage transients appearing between the engine and the support do not appear superimposed on the 10 power supply voltage connected across said solid-state components.

2. The outboard motor unit of claim 1 wherein said ignition system is housed within a metallic housing and having means mounting the housing directly on the frame to establish the 15 ground connection therebetween.

3. The outboard motor unit of claim 2 wherein said ignition system is a capacitor discharge system including a discharge capacitor and a transistorized converter for charging the capacitor, said ignition system being housed within a metallic 20 housing having said converter grounded to the housing and having means mounting the housing directly on the frame to establish the ground connection therebetween.

4. The outboard motor unit of claim 2 wherein said isolating members are rubberlike mounts to vibrationally isolate the 25 cowl frame from the engine and said ignition system being housed within a metallic housing and having means mounting the housing directly on the frame to establish the ground connection therebetween.
